INVENTOR:

MABEL WYNN,
BY

Graham & Rainie

ATTORNEYS.

UNITED STATES PATENT OFFICE.

MABEL WYNN, OF LOS ANGELES, CALIFORNIA.

DESIGN FOR COMBINATION WASHCLOTH AND DOLL.

Application filed February 13, 1924. Serial No. 8,628. Term of patent 3½ years.

To all whom it may concern:

Be it known that I, MABEL WYNN, a citizen of the United States, residing at Los Angeles, in the county of Los Angeles and State of California, have invented a new, original, and ornamental Design for a Combination Washcloth and Doll, of which the following is a specification, reference being had to the accompanying drawing, forming part thereof.

In the drawing, Fig. 1 is a face view of the design for a combination washcloth and doll; and Fig. 2 is a side view of the same.

I claim:

The ornamental design for a combination washcloth and doll, as shown.

MABEL WYNN.
